UNITED STATES PATENT OFFICE.

FRANK BLANDO, OF NEW YORK, N. Y.

PRESS.

Application filed May 10, 1927. Serial No. 190,315.

This invention relates generally to presses employing compressed air.

The primary object of the invention resides in the provision of an assemblage of 5 component parts whereby air at normal atmospheric pressure may be compressed and then transferred for the operation of certain die members in the manufacture of artificial flowers.

10 Another object of the invention is the provision of means for inducing a flow of air into a space and subsequently compressing said air and finally transferring the same to a position for the performance of useful 15 work.

Still another object resides in the provision of means, directly responsive to said air-entry inducing means, for cutting off the flow of air into the device during the 20 pressing operation.

A still further object is to provide means for operating the device during the compression or working stroke, said means being of alternative form; that is, the operation of 25 one of the forms places the other in a position for facilitating the restoration of the parts to a position ready to affect the compression of the fluid, such as air, or the like.

A still further object of the invention is 30 to provide a reciprocatory member having associated therewith yieldable means adapted to facilitate the restoration of said reciprocatory member to its normal position subsequent to the compression stroke.

35 Still further objects and advantages of the invention will become apparent as the description proceeds, and in order that the same may be better understood reference is had to the accompanying drawings forming 40 a part of this specification.

In said drawings:

Figure 1 is a sectional view of my novel 45 press with certain parts broken away.

Fig. 2 is a plan view thereof.

Fig. 3 is a vertical sectional view taken on line 3—3 of Fig. 1 to illustrate certain operating mechanism.

Fig. 4 is a front elevation of said operating mechanism; and

50 Fig. 5 is a transverse sectional view taken on the plane of the line 5—5 of Fig. 1 to depict certain guiding means.

In carrying out the aforesaid objects of the invention, I proposed to provide two 55 cylinders 10 and 11, the former being termed the major cylinder and the latter the minor

cylinder. Within said cylinders are mounted reciprocatory members 12 and 13, the said member 12 being operated directly by certain foot-operated mechanism, while the member 13 is operated by a fluid, such as air, after having been subjected to the influence of said member 12. In other words, there is no direct connection between the reciprocatory member 12 and said member 13, 60 in so far as coordinated mechanical structure is concerned, and this is a feature of the invention.

The broad concept of the invention having been stated, let us consider the detailed 65 structural arrangement of my device and upon reference specifically to Fig. 1, it will be noted that I have provided said cylinder 10 with a basal flange 14, adjacent the open end of said cylinder, there being provided a 70 plurality of fastening devices 15 for anchoring the same to a table 16, or other suitable supporting means. The top of said cylinder is closed by a head 17 having a depending annular flange 18 insertible in said cylinder, 75 said head 17 being centrally bored and threaded, if necessary, for the reception of a pipe 18 connected to a check-valve 19 establishing communication with the atmosphere 80 at certain intervals. Intermediate said pipe 18 is disposed a T-fitting 20 carrying a horizontal pipe 21 leading to the pipe 22, and through the series of pipes aforesaid, the 85 said valve 19, communication is established between said cylinders 10 and 11 and the atmosphere. As shown in said Fig. 1 said cylinder 11 is also provided with a centrally 90 apertured closure member 23 for the obvious purpose of closing the open end of said cylinder and further receiving the lower extremity of said pipe 22, said cylinder 11 being 95 preferably secured to said cylinder 10 by means of a bracket 24, or other suitable arrangement.

Reverting now to the reciprocatory members 12 and 13, it will be observed that the latter is provided with a form of guiding means, such as the stem 25, which slides in the aperture 26 at the bottom closed portion of said cylinder 11, the extreme lower end of 100 said stem 25 being squared, as indicated at 27. In the nomenclature of this art this squared portion is termed the presser bar and is adapted to contact certain dies for the production of artificial flowers, as will 105 presently appear. Said reciprocatory member 13 is further provided with yieldable

means in the form of a spring 28, positioned between said members 13 and the bottom of said cylinder 11. The other reciprocating member 12 is provided with a plunger 29, 5 extending downwardly therefrom through an aperture 30 in the top of said table 16, the lower portion of said plunger being preferably squared as indicated at 31 and having rack teeth 32 cut into the face thereof, which 10 enmesh with a gear wheel 33 mounted on stub shaft 34 supported by the yoke bracket 35 depending from the bottom of the top of said table 16. Disposed on both sides of said gear wheel 33 and rotating in unison therewith, is a pair of rotatable members or pulleys 36 and 37, each having cables 38 and 39 respectively wound thereon, the former cable extending to a foot-treadle 40 and the latter to a similar foot-treadle 41, both being mounted on a shaft 42 journaled in the front legs of said table 16.

Upon inspection of Figs. 1 and 3, it will be observed that said cables 38 and 39 are oppositely wound on their respective pulleys 25 and it is obvious that the unwinding of one cable from its pulley results in the winding of the other cable upon its pulley.

With the parts positioned as shown in Fig. 1, a depression of said treadle 40 causes 30 said cable 38 to unwind from said pulley 36, thus rotating said gear-wheel 33 counter-clockwise and in consequence thereof said plunger 31 slides upwardly and elevates said reciprocating member 12 in said cylinder 10, the air content of the latter being obviously compressed and transferred to said cylinder 11 through the intermediary of the piping just described. The movement of the compressed air of course closes said check-valve 19 and after impinging on said reciprocating member 13 in said cylinder 11, the 35 said member is forced downwardly, compressing said spring 28 and forcing said squared portion 27 or presser bar upon the die plates, (not shown). It should be remembered at this point that said gear-wheel 33 and its companion pulleys 36 and 37 rotate in unison and further that said cables 38 and 39 may be considered as oppositely 40 wound on their respective pulleys. Therefore, the initial depression of said treadle 40, in addition to setting in motion the mechanism described, also operated said pulley 37 and caused its cable 39 to wind thereon and 45 elevate the other foot treadle 41 to a position similar to that previously occupied by its companion treadle 40 and at the termination of the operation of said presser bar 27 upon the die plates, said treadle 41 finds itself in 50 a position for depression, and as will now be pointed out it is the operation of this treadle 41 that materially facilitates the restoration of the parts to the position indicated in Fig. 1.

65 The presser bar 27 having now performed

its operation, as aforesaid, said treadle 41 is depressed and through the medium of cable 39, pulley 37 and gear wheel 33, (now rotating clock-wise), said plunger 29 starts its downward travel carrying with it said reciprocating member 12, thus relieving the pressure of the compressed air and in view of a slight vacuum occurring in cylinder 11 the air therein is withdrawn. The continued descent of said reciprocating member 12 restores the normal atmospheric pressure in cylinders 10 and 11 and at the same time said spring 28 operates on said reciprocating member 13 and restores the presser bar to the position indicated in Fig. 1. During this 70 operation it is of course understood that the check-valve 19 is open to permit the admission of air into said cylinder 10, and further any air positioned below said reciprocating member 12 may escape through the 75 ports 43. Air may also enter said ports during the elevation of said member 12.

In view of the elongated disposition of said plunger 29, I prefer to mount a bracket 44 beneath the table and extend the same to the rear legs of said table, by means of a lateral piece 45. As shown in Fig. 5 a groove 46 is arranged in said bracket 44 to interfit with the squared portion 31 of said plunger. A pressure gauge 47 may be introduced in the 80 piping for obvious reasons.

In my device it will be noted that no outside agency is required to obtain compressed air for pressing the dies, for when the treadle 40 is depressed the member 12 compresses the normal atmospheric pressure into a lesser space as said member ascends. For example, every inch the member 12 is raised there is 113 cubic inches of air compressed in cylinder 11 and the piping connecting said cylinders; when the member 12 has raised, let us say six inches, there has been compressed in a space of 1,237 cubic inches, an additional 678 cubic inches of air. This and much less air compressed will drive member 100 13 and the presser bar 27 down to do the 105 pressing required.

I claim:

1. In a press, major and minor reciprocating members, cylinders confining said members, a conduit connecting said cylinders and establishing communication with the atmosphere at pre-determined intervals, means for elevating said major member for compressing air in its cylinder and yieldable means associated with said minor member for restoring the same to its normal position. 115

2. In a press, major and minor reciprocating members, cylinders confining said members, a conduit connecting the upper ends of said cylinders and establishing communication with the atmosphere at intervals responsive to the movements of said members, foot-operated means for elevating said major member and adapted to position a second 120 125 130

foot-operated means simultaneously in operative position for lowering said major member and yieldable means for facilitating the restoring of the minor member to its 5 normal position.

3. In a press, a major reciprocatory member, a minor reciprocatory member responsive to the movements of said major member, cylinders confining said members, a conduit

connecting said cylinders and establishing 10 communication with the atmosphere, yieldable means associated with said minor member for restoring the same to its normal position and means for operating said major member.

In testimony whereof I affix my signature.

FRANK BLANDO.
